ARSENATE CARRIER PRECIPITATION METHOD OF SEPARATING PLUTONIUM FROM NEUTRON IRRADIATED URANIUM AND RADIOACTIVE FISSION PRODUCTS

Stanley G. Thompson, Daniel R. Miller, and Ralph A. James, Richmond, Calif., assignors to the United States of America as represented by the United States Atomic Energy Commission
No Drawing. Filed Aug. 11, 1947, Ser. No. 768,064
7 Claims. (Cl. 23—14.5)

This invention relates to methods of separating plutonium from contaminating elements and particularly to methods for the separation of plutonium from neutron irradiated uranium and radioactive fission products.

Reference herein to any of the elements is to be understood as denoting the element generically whether in its free state or in the form of a compound unless otherwise indicated by the context.

Plutonium refers to element 94. This element does not occur free in nature but it is ordinarily formed by the reactor of U^{238} with neutrons, a reaction usually carried out in a neutronic reactor of the pile type. In such a reactor neutrons react with U^{238} to form U^{239} which decays with a half-life of 23 minutes to form Np^{239} which in turn decays with a half-life of 2.3 days to form plutonium. The uranium usually used in neutronic reactors is a mixture of U^{238} and U^{235} and during the reaction neutrons also react with the U^{235} to form fission products. These consist mainly of elements with atomic numbers from approximately 35 to 45 and 51 to 60. These fission products are usually highly radioactive and decay to more stable elements by the emission of beta and gamma rays. The radioactivity of these elements is very dangerous to personnel and the material must be handled with extreme care.

The uranium mass as it is removed from the neutronic reactor usually contains a very large percentage of unreacted uranium and a very small percentage of neptunium, plutonium and radioactive fission products, and, in order to obtain plutonium in a usable form, it is necessary to separate plutonium from the unreacted uranium and radioactive fission products.

The uranium mass is commonly permitted to age for a short period in order that the neptunium contained therein may decay to plutonium since neptunium has a half-life of only 2.3 days. However, the separation of plutonium from the other contaminating elements of the mass requires very careful processing. This processing may be arbitrarily divided into three steps. The first step is usually the separation of the plutonium from the uranium and certain of the fission products. This step is usually referred to as extraction. In the second step the plutonium is separated from the remaining radioactive fission products and this step is usually referred to as decontamination. The final step is the plutonium concentration step.

Several methods of separating plutonium from contaminating elements have been worked out. The one

2

most widely used at present is a method based upon the fact that plutonium has several oxidation states and that certain plutonium compounds in the various states have different solubilities. Where plutonium is present in sufficient concentration in the mass of neutron irradiated uranium, the mass may be dissolved and an insoluble precipitate of plutonium may be formed which will remove plutonium from certain dissolved contaminants.

While plutonium may be present in solution in a concentration great enough that it may be directly precipitated from the solution, plutonium is usually present in a neutron irradiated mass of uranium in such small quantity that the plutonium cannot be directly precipitated from a solution formed from the irradiated mass. In this case plutonium may be separated by forming a carrier precipitate which will carry the plutonium from solution. This carrier precipitate for plutonium, usually referred to as the product precipitate, may then be redissolved, the oxidation state of plutonium changed and another precipitate formed in the solution which will not carry the plutonium in its new oxidation state but will carry contaminating elements contained in the solution. This precipitate is usually referred to as a by-product precipitate. In order to increase the efficiency of the carriers in separating plutonium from contaminating elements it is often necessary to add compounds to the solution which will prevent the undesirable elements from being carried with the element which it is desired to remove from solution, by increasing the solubility of the contaminating element. These compounds are referred to as complexing agents. Thus, in the precipitation of plutonium from uranium, sulfate ions may be added to the solution to form a more soluble uranium complex thus preventing the uranium from being carried with the plutonium carrier precipitate.

The principal object of this invention is to provide a novel and simplified method of extracting plutonium from neutron irradiated uranium.

Another object of this invention is to provide a carrier for plutonium in the +4 oxidation state which will not form insoluble compounds with the UO_2^{+2} ion.

Other objects and advantages of this invention will be come apparent in the following detailed description.

We have discovered that plutonium in a +4 oxidation state forms a compound with the arsenate ion which, while soluble in a highly acid solution, is very insoluble in a neutral or basic solution. This compound, which has the formula $Pu_3(AsO_4)_4$, may be formed by the addition of a soluble arsenate compound such as arsenic acid to a solution containing the plutonium ion in the +4 oxidation state followed by neutralization of said solution. This precipitate is a dense crystalline substance which may be easily separated from the supernatant liquid by any of the usual methods. The solubility of $Pu_3(AsO_4)_4$ has been found to be less than 20 mg./l. in 3 N nitric acid. Separation of plutonium from contaminants such as uranium and many of the fission products, particularly the radioactive fission products which do not form arsenates insoluble in aqueous solution, may be

readily effected by simply adding an excess of arsenate ion to an acid solution containing said plutonium, uranium and fission products in an ionized state.

In most neutron irradiated masses containing plutonium the plutonium is present in concentrations so low that the plutonium cannot be directly precipitated from the solution. In such cases it is necessary to use carrier techniques to separate the plutonium. It is desirable to have a carrier precipitate that will be able to carry plutonium from solution quantitatively without precipitating or carrying other undesirable elements contained in solution. In addition, it is desirable that a carrier carry plutonium quantitatively at all concentrations from tracer to the concentration at which plutonium may be directly precipitated and that the conditions of acidity at which the precipitate forms be not so rigid that it is impractical to use the carrier on large scale operations. We have discovered that a carrier of bismuth arsenate fulfills all of these requirements and is a particularly suitable carrier for the extraction of plutonium from a solution of neutron irradiated uranium.

The solubility of bismuth arsenate has been found to be approximately 20 mg./l. in 3 N HNO₃. In 10 N HNO₃ its solubility is about half that of bismuth phosphate. The precipitate is dense and crystalline and thus may be readily separated from solution.

Bismuth arsenate has been found to be a very efficient Pu⁺⁴ carrier. It is believed that the principal reason for its suitability is that the bismuth arsenate precipitate is isomorphous with plutonium arsenate. Thus, it is believed that plutonium ions are incorporated in the crystal lattice structure of bismuth arsenate when that compound is formed in the solution containing the Pu⁺⁴ ion. However, some of the carrying effect may also be due to surface adsorption of the plutonium ion by the bismuth arsenate crystal. Bismuth arsenate has been found to carry plutonium quantitatively at a wide range of concentrations. Thus, the carrying of plutonium is effective not only at tracer concentrations but at all concentrations up to the concentration of plutonium which may be directly precipitated with the arsenate ion.

One aspect of carrying techniques, in which bismuth arsenate has proved itself to be greatly superior to most other carriers, is the wide range of concentrations, and acidity ratio at which a bismuth arsenate precipitate will form, and the efficiency with which bismuth arsenate will carry plutonium throughout this range. Many other plutonium carrier precipitates will carry plutonium ions quantitatively only when the plutonium is present in solution within narrow concentration limits, or will fail to separate plutonium ions from other contaminating ions, unless the precipitation is carried out within very narrow acidity concentration limits. Numerous experiments have been carried out to determine the carrying power of bismuth arsenate for plutonium over a wide range of concentrations and reaction conditions. The conditions and results of some of these experiments are summarized in Table I following:

One phase of this invention is concerned with the separation of plutonium from a solution formed by dissolving in an inorganic acid a mass of uranium which has been irradiated with neutrons in a neutronic reactor employing a chain reaction. Plutonium ions are present in said solution in a valence state not greater than +4 and in a concentration greater than tracer but less than that from which plutonium compound could be directly precipitated. The neutron irradiated uranium mass also contains small quantities of fission products with the concentration approximately equal to that of the plutonium. The concentration of the uranyl nitrate hexahydrate has been adjusted in the solution so that it is below about 22% in order that the loss of element 94 in the extraction process be kept to a minimum.

By the process of this invention a source of arsenate ion and preferably arsenic acid is added to the solution. The acidity of the solution is then adjusted, depending upon the acid used and whether a complexing agent for the uranyl ion is employed so that upon the addition of a soluble bismuth compound a precipitate of bismuth arsenate will form which will carry the plutonium ions present in solution but not the uranyl ions. Although a precipitate may be formed with the solution at room temperature it has been found preferable to heat the solution prior to the addition of the bismuth ions to a moderate temperature of for example 75° C. and somewhat better results have been obtained by digesting the precipitate for a period of one to two hours. As little as 1.5 mg./ml. of bismuth ion has been found to be a sufficient concentration to form a precipitate; however, this may be increased depending upon the acid used in the solution and the acid concentrations. A suitable source of bismuth ion has been found to be the bismuth nitrate but other soluble bismuth salts, for example the sulfate or halides may be used.

The acid normally used to dissolve the uranium mass is nitric acid and this is an entirely suitable medium in which to form the bismuth arsenate precipitate. However, some other inorganic acids may be used and a mixture of nitric and sulfuric acids has been found to be particularly suitable for the formation of the arsenate precipitate.

One embodiment of this invention is concerned with the separation of plutonium from uranium without the use of a complexing agent for the uranyl ion. In most other processes for the separation of plutonium from uranium the difference in solubility between the plutonium salt formed with the carrier and the uranyl salt formed is so small that without the use of a complexing agent a substantial percentage of the uranyl ion is carried with the product carrier precipitate. In order to avoid forming a uranyl compound which will be carried with the plutonium carrier precipitate, a complexing agent is used to increase the solubility of the uranyl ion and this is commonly a soluble sulfate compound. Plutonium arsenate, however, is more insoluble and uranium arsenate more soluble than the corresponding compounds for most other carriers so that plutonium may be carried from solution

TABLE I

Carrying of plutonium by BiAsO₄

Exp. No.	Percent UO ₂ (NO ₃) ₂ ·6H ₂ O	HNO ₃ conc., N	AsO ₄ ⁻³ conc., M	Bi conc., mg./cc.	H ₂ SO ₄ conc., N	Digestion conditions		Percent Pu precipitated

substantially quantitatively and uncontaminated by uranium by a bismuth arsenate carrier precipitate.

Another advantage of this process is that bismuth arsenate carries plutonium quantitatively under a rather wide range of conditions of acid concentration and plutonium ion concentration. This flexibility makes this process particularly suitable for large-scale operations in which rigid acidity concentration requirements would decrease the feasibility of the extraction process. The use of the process of this invention for the extraction of plutonium without a uranyl ion complexing agent may be illustrated by the following example.

EXAMPLE I

A mass of neutron irradiated uranium was dissolved in a nitric acid solution and the concentration of the uranyl nitrate hexahydrate was adjusted to 20% of the solution. The nitric acid concentration was then adjusted to 1 N. Arsenic acid was added to make the solution 0.1 M and the solution heated to 75° C. A quantity of $\text{Bi}(\text{NO}_3)_3$ sufficient to give a concentration of 1.5 mg. of Bi^{+3} per ml. of solution was added to the solution and the solution digested for two hours at 75° C. with mechanical agitation. The solution was then filtered to remove the carrier precipitate. Tests of the carrier precipitate showed that 99.3% of the plutonium had been extracted. This experiment was repeated numerous times with the nitric acid concentration being varied between 0.5 and 1.0 N and this sequence of experiments disclosed that this process worked equally well throughout this range of concentrations with at least 98% of the plutonium being carried in all cases.

Where a complexing agent such as sulfate ion is not used in the extraction phase it has been found that the conditions for achieving maximum efficiency for the extraction step are as follows: If the H_3AsO_4 concentration is 0.1 M no uranyl arsenate precipitates, if the HNO_3 concentration is about 0.5 N. If the solution is 1 N in HNO_3 the H_3AsO_4 concentration should be maintained below 0.15 M to avoid uranyl arsenate precipitation.

Although comparatively satisfactory carrying of plutonium may be achieved by the process of this invention without a complexing agent for the uranyl ion, it is also possible and in many cases desirable to use a uranyl ion complexing agent for the extraction of plutonium since a still wider range of acid concentrations may then be used. The normal complexing agent used is the sulfate ion and this may be added to the solution either as a soluble sulfate salt or by the use of sulfuric acid to adjust the acidity of the uranyl nitrate hexahydrate solution. It has been found that if the H_3AsO_4 concentration is 0.4 M and the total additional acid concentration

is 1 N the H_2SO_4 concentration should be equal to or greater than 0.5 N. The use of the process of this invention for the extraction of plutonium with a complexing agent present may be illustrated by the following example.

EXAMPLE II

Neutron irradiated uranium was dissolved in nitric acid to achieve a 20% uranyl nitrate hexahydrate solution. The nitric acid concentration was then adjusted to 0.2 N and sulfuric acid added to make the solution 1 N in total acid concentration. Arsenic acid was then added to the solution to .50 M concentration and the solution heated to 75° C. A quantity of $\text{Bi}(\text{NO}_3)_3$ sufficient to give a concentration of 2.5 mg. of Bi^{+3} per ml. of solution was then added to the solution and the solution digested for two hours at 75° C. The bismuth arsenate precipitate was separated by centrifugation and it was found that 99.4% of the plutonium was carried with the precipitate.

During the extraction step plutonium is separated from uranium and from a majority of the fission products; however, there are certain fission products which are iso-

morphic with plutonium in the +4 valence state and these fission products are usually carried with plutonium by the carrier precipitate. In order to separate plutonium from these fission products, a decontamination step is carried out whereby the plutonium is oxidized to the +6 oxidation state and a by-product carrier precipitate with these fission products formed and separated. Fission products which are most troublesome in this step are zirconium and niobium. In other processes the carrier precipitate often forms such insoluble compounds with the zirconium and niobium that when the carrier product is dissolved following the extraction step these fission product precipitates are not completely dissolved and their presence leads to product loss in the fission by-product precipitate and to low decontamination factors. Investigation has disclosed, however, that the arsenates of zirconium and niobium are sufficiently soluble that this difficulty is precluded in the process of this invention.

The process of this invention may be used for the complete extraction and decontamination of plutonium. Thus, the plutonium may be extracted as described above and following this extraction the carrier precipitate may be dissolved in an inorganic acid, the plutonium oxidized to the +6 state and a by-product carrier of bismuth arsenate precipitated and separated from the solution. To complete the decontamination cycle, the Pu^{+6} ions may then be reduced and removed from solution by precipitating with a carrier precipitate of bismuth arsenate. This decontamination cycle may be repeated as often as necessary to obtain the desired concentration. In another embodiment, however, the bismuth arsenate extraction process may be combined with other methods of decontamination, for example with the bismuth phosphate decontamination process. The combination of the process of this invention and the bismuth phosphate decontamination process may be illustrated by the following example.

EXAMPLE III

A neutron irradiated uranium mass was dissolved in nitric acid to produce a 20% solution of uranyl nitrate hexahydrate and the solution was then adjusted so that it contained 1 N HNO_3 and 0.4 M H_3AsO_4 . A quantity of $\text{Bi}(\text{NO}_3)_3$ sufficient to give a concentration of 1.5 mg. of Bi^{+3} per ml. of solution was added to the uranyl nitrate hexahydrate solution. The solution was then digested for two hours with mechanical agitation at 75° C. to insure complete precipitation of the bismuth arsenate plutonium carrier. The plutonium carrier precipitate was separated by centrifugation, and a decontamination cycle carried out with the precipitate, using the standard bismuth phosphate method. This cycle comprised dissolving the product precipitate, that is the plutonium carrier precipitate of bismuth arsenate, in a nitric acid solution, oxidizing the plutonium ions to the +6 valence state with NaBiO_3 , forming a by-product carrier precipitate of BiPO_4 in the solution, and separating this precipitate with accompanying fission products from the solution. The Pu^{+6} ions were then reduced with ferrous ions, and the reduced plutonium ions precipitated from the solution with a carrier of BiPO_4 . Counter analysis showed that the product precipitate contained 98.3% of the plutonium present in the original solution, and that an overall decontamination factor of 2230 for β rays, 164 for γ rays was obtained.

In order to compare these results with those obtainable with the standard bismuth phosphate procedure for plutonium extraction and decontamination, an experiment was carried out with an equal quantity of uranyl nitrate hexahydrate containing the same amount of plutonium and fission products as that used in the preceding experiment, but using the standard bismuth phosphate procedure. The extraction cycle differed from that of the previous experiment in that the product carrier precipitate was bismuth phosphate rather than bismuth arsenate. The procedure followed in the decontamination cycles of the two experiments was the same. The advantages of

7 using the bismuth arsenate process are clearly shown by the results obtained, which are tabulated below.

8 tity to furnish a maximum concentration of 0.4 M., contacting the solution with a soluble bismuth compound,

Fraction	Experiment I			Experiment II		
	BiAsO ₄ Extraction Cycle			BiPO ₄ Extraction Cycle		
	BiPO ₄ Decontamination Cycle			BiPO ₄ Decontamination Cycle		
	Plutonium Content, Percent	Beta Activity, Percent	Gamma Activity, Percent	Plutonium Content, Percent	Beta Activity, Percent	Gamma Activity, Percent
Original Solution	100	100	100	100	100	100
Extraction Cycle Product ppt.	99.4	10.9	20.7	97.2	22	13
Decontamination Cycle Product ppt.	98.3	0.045	0.61	90.9	0.33	1.37

Instead of using the bismuth phosphate oxidation-reduction procedure as described above for the decontamination cycles, other procedures may be used with the process of this invention.

While there have been described certain embodiments of our invention it is to be understood that it is capable of many modifications. Changes therefore may be made without departing from the spirit and scope of this invention as described in the appended claims.

What is claimed is:

1. A method of separating plutonium from an aqueous solution which comprises precipitating the plutonium as plutonium arsenate.

2. In a process of separating plutonium from an aqueous solution, the step which comprises co-precipitating plutonium with bismuth arsenate.

3. The method of separating plutonium from uranium and radioactive fission products which are non-isomorphic with the plutonium ion in the +4 oxidation state, which comprises co-precipitating plutonium with bismuth arsenate.

4. The method of separating plutonium from uranium contained in an inorganic acid solution, which comprises co-precipitating plutonium with bismuth arsenate.

5. In a method of separating plutonium contained in an inorganic acid solution in an oxidation state of not greater than +4 from uranium, the step which comprises co-precipitating plutonium with bismuth arsenate.

6. The method of separating radioactive niobium values from hexavalent uranium values contained in an aqueous solution which comprises forming a 0.5-1.0 N nitric acid solution containing said niobium values and uranium values, adding orthoarsenic acid to said solution in a quan-

whereby a bismuth arsenate carrier precipitate containing niobium is formed, and separating said precipitate from the solution.

20 7. The method of separating radioactive zirconium values from hexavalent uranium values contained in an aqueous solution which comprises forming a 0.5-1.0 N nitric acid solution containing said zirconium values and uranium values, adding orthoarsenic acid to said solution in a quantity to furnish a maximum concentration of 0.4 M, contacting the solution with a soluble bismuth compound, whereby a bismuth arsenate carrier precipitate containing zirconium is formed, and separating said precipitate from the solution.
